ROOFING TILE

Fritz Koch, St. Paul, Minn.

Application April 14, 1930. Serial No. 444,131

2 Claims. (Cl. 108—10)

Roofing constructed from burned ceramics or tile has advantages of permanence and artistic appearance, but heretofore its cost has greatly exceeded that of good grades of wooden shingles. Further, the weight of the tile in the completed roof has been many times that of such shingles so that where an old roof of the latter type has required recovering it has been necessary, in most cases, if tile is to be employed, to greatly reinforce the roof supports. By my improvements, I afford a tile roof at a cost about equal to that of good cedar shingles and at the same time make it possible to cover an old roof with artistic tile, in most cases, without reinforcement of the supports.

There are two general classes of economies which are effected by my roofing, namely, first those which relate to the tile form and manufacture of relatively thin, burned units, including handling thereof prior to placing them on the roof; and second, those which relate to the construction of a roof from such tile. The present invention is chiefly concerned with the first class of economies, while the second class is more fully described and claimed in my copending application for patent for Improvements in tile roof and method of constructing the same, Serial No. 469,557, filed July 21, 1930.

Succinctly stated, it is the object of the present invention to provide a durable roofing tile of unusually light weight and low cost adapted to be employed to construct a roof of artistic appearance with a minimum of labor and structural materials.

Further objects are to minimize the work of handling the tiles, to facilitate the construction of a roof neatly and quickly and to minimize losses due to cracking and warping during the drying and burning operations.

In the drawing which illustrates the best form of my improved tile at present known to me, Figure 1 is an end view of one of the tile blocks; Fig. 2 is a plan view of the same, with the normal location of the fastening nail indicated; Fig. 3 is a plan view illustrating the arrangement of a group of tile units on the roof, with portions of two of the units broken away to show the attaching means; Fig. 4 is a fragmentary section through one of the nail slots, taken on the line 4—4 of Fig. 2; Fig. 5 is a similar section taken on the line 5—5 of Fig. 2 and Fig. 6 is a fragmentary section taken on the line 6—6 of Fig. 3.

I employ as the raw material for my improved tile a suitable clay which is ground and reduced to the desired plastic consistency for extruding

through a die. An auger machine of any suitable or well known construction is used for the extruding operation and contains a die constructed to form a continuous, tubular body like that illustrated in Fig. 1. This tubular body is cut into sections of the desired, uniform length, preferably equal to the length of the shingle units. Tile blocks about 12 inches in length and about 5 inches in diameter with walls approximately one-half inch thick at the thickest point can be handled readily and are well suited for my purposes. Four individual tile or shingle units 7 are thus formed of equal size and arranged symmetrically around the circumference of each tile block.

Extending along the side edge of each shingle unit 7 is a curved portion 8 which diminishes in thickness toward its outer edge. In the tile blocks the units are connected by naturally weak lines of cleavage 9 (Figs. 1 and 2). The central portion of each unit is straight and has plane inner and outer surfaces which are of equal width. An arrow 10 (Fig. 1) indicates the radius of curvature of the outer curved surface of each tile and an arrow 11 indicates the radius of curvature of the inner surface, both surfaces being cylindrical. These radii 10 and 11 are equal and the centers from which the radii of adjacent tile edges extend are indicated on the dotted construction lines 12 which are perpendicular to each other and to the plane surfaces of the straight segments. Thus it will be evident that the inner and outer surfaces of each tile unit are alike so that one unit is adapted to fit in nesting engagement with another, as clearly shown in Fig. 6. Each tile block, while green, is formed with at least two slots extending through the tile units near one end to receive nails or like means for securing the units to a roof. These slots 13 are wedge-shaped with the narrow end of the slot adjacent to the normally upper end of the tile unit. The larger end of the slot 13 is of such size as to permit the free passage therethrough of the head 14a of a nail 14, or other securing means. An enlargement 13a of the slot 13 near the outer surface of the tile block permits the head 14a to be counter-sunk, as clearly shown in Figs. 4, 5 and 6. Proper location and uniformity of the slots 13 in the several tile units is insured by suitable automatic perforating mechanism.

The green tile blocks described above are now dried at a temperature of 80 to 140 degrees Fahrenheit for a period of from twenty-four to thirty-six hours and are then placed in an oven and burned at a temperature of about 2000 to 110

2200 degrees Fahrenheit for a period of three to five days. Obviously, these temperatures and periods of drying and burning may be varied and are dependent on the composition of clay employed as well as the thickness of the walls of the tile block.

During shipping and handling and until they reach the location of the roof to be covered, the tile units may be retained in the block form.

10 To separate the several units of a block it is only necessary to deliver a slight blow directed transverse the tubular body when the four units fall apart and separate almost universally along the straight, weakened lines 9.

15 In constructing a roof covering with my improved tile, the units are preferably arranged as shown in Figs. 3 and 6. Half of the tile are placed with their curved side edges extending up and the other half with the edges turned down. Those in the first mentioned position are hereinafter designated as foundation tile because they are adjacent the roof. The foundation tile are indicated by the numeral 7a adjacent to a roof 15. The tile disposed with their curved edges extending down are indicated at 7b and are called the cover tile.

The tile are placed on the roof in successive, overlapping courses. Beginning at the lower edge of the roof a horizontally extending course 30 of the foundation tile 7a is first laid, these tile being placed in spaced relation to each other. They are secured to the roof by the use of nails engaging in the slots 13 near their upper ends. Upon the row of foundation tile thus laid, a 35 course of cover tile 7b is placed in overlapping relation to the curved side edges of the first course and covering the space between the tile. The upper ends of the cover tile in the first course are located a short distance below the upper ends 40 of the first course of foundation tile and said cover tile are secured by the use of the nails 14. Another course of foundation tile may now be laid with the lower ends of the tile overlapping the upper ends of the first course of foundation 45 tile and abutting the upper ends of the first course of cover tile, as indicated at 16 in Fig. 3, where portions of the cover tile are broken away. The second course of foundation tile need not be secured to the roof as they are held in place by 50 the overlapping edges of the cover tile and are prevented from sliding down the roof by the cover tile of the course beneath. Successive courses of alternate foundation and cover tile are thus laid with the courses of cover tile lap- 55 ping the upper ends of the course beneath and concealing the rows of nails 14 and slots therefor.

Proper placing of the successive courses is insured by locating the nails 14 in uniformly spaced relation on the roof, and projecting therefrom 60 the proper height, prior to the placing of the tile. The method of procedure to secure this result is more fully described in my copending application for patent on tile roof and method of constructing the same, but it is important to note that the 65 tile of the present invention is designed for use with such method. When the nails have been properly located on the roof successive courses of foundation and cover tile are arranged as above described and are secured in place by merely passing a head of a nail 14 through the large end of each slot 13 and then sliding the tile down the roof a short distance to cause a firm gripping of

the nail in the narrow end of the slot. The heads of the nails are counter-sunk so as not to interfere with the proper nesting of the overlying course of cover tile.

Accidental removal of a tile is prevented because movement up the roof, such as is necessary to disengage the nail from the wedge slot, must be accompanied by a raising of the cover tile and movement of at least two of the foundation tile in the superimposed course up the roof. Notwithstanding this secure fastening of the tile to the roof, when and if repairs are necessary, it is easy to manually detach selected units and replace them because of the detachable connecting means. It will now be understood that the foundation tile form continuous troughs extending from the top to the bottom of the roof and the cover tile form ridges which shed the water into such troughs. The capacity of the troughs thus formed to carry off an ample amount of water is insured by my arrangement of the straight central portions with the upturned edge portions extending beneath the lapped edges of the cover tile. Facility in placing the tile on the roof and a stable condition in the finished roof are further 100 benefits secured by providing the straight central portions on the tile. As best shown in Fig. 6, there are two lines of contact between the side edges of each foundation tile and its overlying cover tile and between these lines of contact there 105 is a chamber having sufficient capacity to guard against the tendency of the wind to drive small streams of water past the overlapping edges during wind storms. These various features combine to make an unusually leak-proof roof.

By my symmetrical arrangement of the tile units around the circumference of the block and the absence of any projections, I secure uniform drying around the circumference of the tubular body and throughout the walls thereof. This is 110 an important feature of the invention because I thereby practically eliminate the heretofore troublesome cracking and warping of the tile units during drying and burning. Obviously the side edges of the units must be straight in order 115 to secure a proper fitting of the individual tile together on the roof. The tubular type of tile body has the further advantage of facilitating the handling of the tile and keeping the units together in sets of perforated and unperforated 120 units.

Having described my invention what I claim as new and desire to protect by Letters Patent is:

1. A roofing tile having a wide, flat central portion, and relatively narrow curved edge portions 130 diminishing in thickness toward their outer edges and the inner and outer surfaces of the tile being of like width and degree of curvature to permit the fitting of the inner surface of one tile in continuous face to face contact with the outer surface of another tile.

2. A roofing tile having a wide, flat central portion formed with plane inner and outer surfaces of equal width and relatively narrow, curved side portions having inner and outer surfaces of cylindrical form, the radius of curvature of the inner surface of each side portion being equal to that of the outer surface of said portion and the tile being of uniform cross sectional shape and size from end to end.

FRITZ KOCH.
